UNITED STATES PATENT OFFICE.

FRANK M. BURTON, OF SAN ANTONIO, TEXAS.

FUSE CARRIER.

1,405,271.

Specification of Letters Patent. Patented Jan. 31, 1922.

Application filed April 28, 1919. Serial No. 293,078.

To all whom it may concern:

Be it known that I, FRANK M. BURTON, a citizen of the United States, residing at San Antonio, in the county Bexar and State of Texas, have invented new and useful Improvements in Fuse Carriers, of which the following is a specification.

This invention relates to fuse holders and aims to provide a holder which carries a number of fuses, capable of being brought into proper position to provide a fresh fuse in the event of the burning or blowing out of one of the fuses.

Another object is the provision of a fuse holder having therein a removable fuse carrier, so that should all of the fuses become useless, the carrier may be removed and a new one substituted.

Another object is the provision of a fuse holder which carries a plurality of fuses held under strong tension, means being provided upon the casing whereby a fresh fuse may be moved into position after the one which has been in use has burned out.

Other objects and advantages of the invention will appear as the following description is read in connection with the accompanying drawings.

In the drawings:

Figure 1 is a perspective view of a fuse holder embodying the present invention.

Figure 2 is a sectional view.

Figure 3 is a plan view.

Figure 4 is a sectional view on the line 4—4 of Figure 2.

Figure 5 is a similar view on the line 5—5 of Figure 2.

Figure 6 is a sectional view with the top of the casing removed.

Figure 7 is a sectional view on the line 7—7 of Figure 3.

Figure 8 is a detailed perspective view of the fuse carrier or spool.

Referring to the drawings in detail, wherein like characters of reference denote corresponding parts, the fuse holder comprises a casing 10, formed of suitable insulating material, one end of the said casing being provided with a threaded metallic thimble 11, by means of which the casing may be movably positioned for use.

One end of the casing is open, as shown and extending through its opposite end is a pin 12, the outer end of the pin serving as a contact terminal, which engages the receiving socket in the usual manner.

The pin 12 extends approximately the entire length of the interior of the casing and has slidably and rotatably mounted thereon a sleeve 13, which is provided with a finger 14 disposed parallel to the pin 12. Mounted upon the pin 12 between the sleeve and the bottom of the casing is a coiled spring 15, one end of this spring being secured to the sleeve and its opposite end to the pin, the casing or other permanent or stationary support. By this means the sleeve is capable of both yielding longitudinal and rotary movement upon the pin.

Slidably and rotatably mounted upon the pin 12 is a spool 16, one end of the spool being formed of suitable insulation and indicated at 17. This end is provided with a notch 18, which is adapted to receive the finger 14 when the spool is placed upon the pin. The opposite end of the spool is formed of a metallic disc 19, which is connected to the insulated end 17 by means of a metallic connecting sleeve 20, the pin 12 being received within this sleeve.

The metallic connecting sleeve 20 extends through the disk 19 and extending radially from this sleeve to the outer edge of the disk is a strip of metal 21. The outer end of this strip is located adjacent one end of one of a plurality of fine wire fuses 22, the opposite ends of these wires being connected to the insulated end 17 of the spool. Positioned above the ends of the remaining fuse wires 22 are lugs 21^a, the purpose of which will be hereinafter explained.

Extending radially into the interior of the casing 10 is a metallic finger 23, the latter being connected to the sleeve 11 through the medium of a suitable conductor 24.

In assembling the device, the spool is positioned over the pin 12, so that the finger 14 enters the notch 18, the said spool being then rotated against the action of the spring 15 until the notch 18 is brought into register with the radial finger 23. The spool is then further depressed against the spring 15, so that the insulated end 17 of the spool will pass the radial finger 23, whereupon a further rotation of the spool will cause the said finger to engage the upper face of the said insulated end in a manner to permit of the rotation of the spool but to hold the same against outward movement. For the purpose of determining the proper position of the notch 18 for the depression of the spool, there is provided a notch 25 in the disc 19,

the said notch registering with the notch 18 in the opposite end of the spool. The face of the disc 19 may be numbered to distinguish the fuse strips 22 and the amperage of the fuses may be also imprinted upon the face of this disc.

The upper end of the casing 10 is removably covered by a lid or closure 26, which is formed of inner and outer insulated discs 27 and 28, which carry a metallic flange 29. Mounted for sliding movement within a slot 30, formed in the disc 28, is a guide 31, which is normally held at one end of the slot through the medium of a spring 32. The guide 31 carries a finger 33 which projects inwardly through a slot in the disc 27 in the path of movement of the strip 21, and the lugs 21^a so as to act as a stop and prevent rotation of the fuse carrying spool, due to the action of the spring 15. Connected to the guide 31 is an insulated button 34, which serves as a means for moving the finger 33 inward, so as to disengage the latter from the lug of the burned fuse strip. Should this be necessary, both of the discs 27 and 28 are provided with registering openings 35, which are closed by means of a mica disc which is clamped between both of the insulated discs. This provides a sight opening, by means of which the fuse carrier may be seen to determine the condition of the fuses.

In the event of one of the fuses being blown or burned out, the tension of the spring 15 will cause a rotation of the fuse carrier after the finger 33 has been moved from engagement with the remains of the burned fuses, this rotation being stopped when the next perfect fuse engages the said finger, whereupon the circuit will be again established.

The cover or lid is removably held in position by means of a spring arm 37, the inner ends of which are pivoted to the casing, as shown. The open end of the casing cover is provided with a lip 38, so that the lid will always be properly positioned upon the casing.

The invention is susceptible of various changes in its forms, proportions and minor details of construction and the right is herein reserved to make such changes as properly fall within the scope of the appended claims.

Having described the invention, what is claimed is:

1. A fuse holder embodying a casing formed of insulating material, a rotatably mounted spring actuated fuse carrier therein, a plurality of fuses carried thereby, a cap for said casing and movable means carried

by the cap and engageable with the fuse carrier to hold the latter against rotation.

2. A fuse holder embodying a casing formed of insulating material, a rotatably mounted spring actuated fuse carrier therein, a plurality of fuses carried thereby, a cap for said casing and a spring actuated stop engageable with the fuse carrier and guided in said cap to hold the fuse in proper position.

3. A fuse holder embodying a casing formed of insulating material, a rotatably mounted spring actuated fuse carrier therein, a plurality of spaced stops carried by said carrier, a cap for the casing, a stop carried by the cap and normally engageable with the stops of the fuse carrier and means whereby the cap carried stop may be moved to permit of rotation of the carrier.

4. A fuse holder embodying a casing formed of insulating material, a rotatably mounted spring actuated fuse carrier therein, a plurality of fuses carried thereby, a stop for each fuse, a cap for the casing, movable means carried by the cap and located in the path of the fuse stops and capable of operation to permit of rotation of the carrier.

5. A fuse holder embodying a casing formed of insulating material, a rotatably mounted spring actuated fuse carrier therein, a plurality of fuses carried thereby, a cap for the casing, and movable means engageable with the fuse carrier to hold the latter in position.

6. A fuse holder embodying a casing formed of insulating material, a pin located therein and adapted to form one fuse terminal, a spring actuated member rotatably and slidably mounted on said pin, a plurality of fuses carried by said member, a stop projecting into the casing and contacting with said member to hold the latter against sliding movement, said stop forming the other fuse terminal, a cap for said casing and means extending within the casing and engageable with said member for holding the latter against rotation.

7. A fuse holder embodying a casing formed of insulating material, a pin located therein, a spool mounted for rotation on said pin, fuses carried by the spool, a spring actuated slidably mounted rotatable collar carried by the pin, means for detachably engaging the collar and spool and a stop projecting within the casing and engaging the spool to prevent sliding movement, a cap for said casing and movable means also projecting into the casing for engagement with the spool to hold the latter against rotation.

In testimony whereof I affix my signature.
FRANK M. BURTON.
